UNITED STATES PATENT OFFICE

1,945,066

MOTOR CONTROLLER

Emanuel Nielsen, Racine, Wis., assignor to Hamilton Beach Manufacturing Company, Racine, Wis., a corporation of Wisconsin

Application September 29, 1932
Serial No. 635,357

2 Claims. (Cl. 74—81)

This invention relates to motor controllers and more particularly to a foot operated controller adapted for governing the speed of a motor such as a sewing machine motor, although obviously 5 the invention may be used to control motors for operating other machinery.

As shown, the invention is embodied in a motor controller of the type disclosed in United States Letters Patent No. 1,772,361 issued August 5, 1930. 10 In foot operating the motor controller shown in said patent it has been found that the controller has a tendency to move relatively to the floor, away from the foot of the operator, especially at the times when the foot of the operator is being raised or lowered to vary the motor speed.

One of the objects of the present invention is to obviate the tendency of the controller to move relatively to its support and to provide 20 means whereby the controller may be foot operated conveniently and efficiently and retained in its intended position without being fastened to a supporting surface.

In the drawing—
25 Fig. 1 is a side elevation of a motor controller embodying my invention.

Fig. 2 is a plan view of the same.

Fig. 3 is an end view of the controller as viewed from the left hand end of Fig. 1.
30 The controller cage or housing, indicated as a whole at 10 in the drawing, is intended to enclose controller mechanism of the character shown and described in said United States Letters Patent No. 1,772,361 or any other suitable controller mechanism which is compact in form and 35 adapted to be actuated by a treadle plate located externally of the housing 10.

The housing 10 is preferably made of sheet metal and consists of a flat bottom 12, longitudinally extending, upright side walls 13, 13, 40 preferably integral with the bottom 12, end members 14 and 15 and a top 16. The parts 14, 15 and 16 are preferably made of one piece of metal screen. The opening 11 is cut in one 45 of the side walls 13 adjacent the end wall 14.

A treadle plate 17 is pivotally mounted at 18 on the controller housing 10. The treadle plate comprises a top surface 19 and downturned side flanges 20 and 21, which at their pivoted ends 50 embrace the sides 13, 13. The side flange 21 terminates in a depending arm 22. The pivot pin 18 extends through the downturned side members 20 and 21 of the treadle 17 and through the side walls 13 of the controller housing 10.

55 The depending arm 22 is provided with inwardly

directed projections 23 for contacting with the extension 24 of a bracket on which a movable controller arm is mounted, as is fully disclosed in the aforementioned United States Letters Patent No. 1,772,361.

At its raised end the treadle plate 17 is provided with a pair of extensions or ears 25 which are preferably continuations of the depending sides 20, 21 of the treadle 17 and are disposed in vertical planes. A roller 26 having trunnions 27 at its ends is rotatably mounted in the ears 25. The surface of the roller 26 is knurled to provide a gripping surface to be engaged by the operator's foot. The roller is preferably as long as the width of the treadle plate.

Preferably the side walls 13, 13 of the rheostat housing have ears 28 formed on their upper edges, which function as stops for the treadle plate 17 when the latter is depressed. A coiled spring 29 located between the top 16 of the housing and the treadle plate 17 returns the plate 17 to its normal position when pressure on the plate is relieved.

If desired, the bottom 12 may be provided with 80 rubber feet (not shown).

The provision of the roller on the treadle plate prevents unintended movement of the controller on its support when the operator depresses or releases the treadle plate 17. The friction of the sole of the operator's shoe against the treadle plate is eliminated by the provision of the roller which revolves relatively to the plate when pressed down or released.

Changes may be made in details of construction without departing from the scope of my invention and I do not intend to be limited to the exact form shown and described, except as set forth in the appended claims.

I claim:

1. A motor controller comprising a portable housing, a treadle plate extending over said housing and having pivotal connection with the housing adjacent one end thereof, spring means cooperating with said housing and the treadle plate to normally maintain the free end of said plate elevated above said housing, a roller rotatably mounted in the free end of said treadle plate, and stop means extending between said housing and plate to space said roller from said housing when the plate is depressed, whereby the tendency of the housing to move relative to its support during operation of the treadle plate is eliminated.

2. A motor controller comprising a portable

housing, a treadle member pivotally connected with the housing adjacent one end thereof, spring means cooperating with said housing and treadle member to normally maintain the free end of said member elevated with respect to the housing, a roller rotatably mounted adjacent the free end of said treadle member, said housing

and treadle member being so constructed and arranged as to insure free rotation of said roller on its mounting throughout its entire operating range, whereby tendency of the housing to move relative to its support when the treadle member is depressed is eliminated.
